Primary Examiner — Karen S Acker*Assistant Examiner* — Elizabeth S Ko(74) *Attorney, Agent, or Firm* — BUCHANAN INGERSOLL & ROONEY PC(57) **CLAIM**

The ornamental design for an antenna-fixing bracket, as shown and described.

DESCRIPTION

FIG. 1 is a front, left side perspective view of an antenna-fixing bracket showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof showing the antenna-fixing part of the article in a tilted position;

FIG. 9 is a perspective view thereof with the part in a second position; and,

FIG. 10 is a reference perspective view thereof, in a state of use with an antenna attached.

The broken lines and unshaded areas in the drawings depict portions of an antenna-fixing bracket that form no part of the claimed design. The additional broken lines which are shown in FIG. 10 depict environmental subject matter that fauns no part of the claimed design.
